ROWBOAT ATTACHMENT

Victor E. Ankarlo, Dolton, Ill.

Application August 29, 1946, Serial No. 693,652

2 Claims. (Cl. 9—25)

1

This invention relates to certain new and useful improvements in rowboat attachments and has for its principal object the provision of an improved construction of this character which will be highly efficient in use and economical in manufacture.

The invention more particularly has concern with the oarlocks of a rowboat, the principal provision of which is to permit a boatsman to sit in the rowboat facing the direction of movement of the boat.

The important object of the invention is the provision of an oarlock comprising few parts, with the result that the same may be manufactured at an economical cost.

Yet another, an equally important object of the invention, is the provision of an oarlock which may be detachably connected to the gunwale of the boat, in proper position with respect to the seat to be occupied by the boatsman thereby affording the rowing operation with the minimum effort on the part of the boatsman.

A further, and equally important object of the invention, is the provision of an oscillatory mounting frame on which are pivotally supported complementary or bearing portions inter-connected for pivotal movement in opposed directions with respect to each other by means of groove and cable connections, the arrangement being such that there are no teeth employed which would otherwise be likely to break by virtue of the force applied to the oar portions, nor parts which would otherwise lock together and thus interfere with the smooth and easy operation of the oar bearing portions.

Another object of the invention is the provision of preventing the detachment of the oar portion bearing frame from the gunwale brackets thus resulting in a structure having a maximum of safety.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a standard rowboat of an approved construction showing my invention associated therewith;

Fig. 2 is a perspective view of my invention;

Fig. 3 is a fragmentary plan view of the same;

Fig. 4 is a side elevational view of the same;

Fig. 5 is a side elevational view similar to that shown in Fig. 4 but showing a slightly modified form of construction and

Fig. 6 is an elevational view of the gunwale clamp embodied in the invention but showing a modified form of construction over that shown in Fig. 2.

2

The preferred form of construction by which the many objects of my invention are accomplished is shown in the accompanying drawings. In this connection, a rowboat of a standard and approved form of construction is indicated at 10 and includes, in addition to the side walls 11 and bottom wall 12, the usual seats 13.

The side walls 11 are capped by the usual gunwales 14. It is with such a boat that my improved oarlock is adapted to be used whereby to enable the boatsman to occupy a seat so as to face the direction of travel of the boat, in which position he may have a clear vision of his path of travel.

In use, a pair of oarlocks are employed. One of the oarlocks is shown in Fig. 2. These oarlocks are of the same construction and operate in the same manner.

The oarlock illustrated in Fig. 2 comprises a clamping structure 15 comprising an elongated spacing rod or bar 16 at the opposite ends of which are clamps 17 and 18. Each of these clamps includes a clamp plate 19 adapted to cooperate with a clamp screw 20 threadedly supported by a bearing 21 formed as an integral part of a connecting bar 22. This clamp plate 19 is adapted to be clamped to the gunwale 14 in the manner shown in Fig. 1.

The clamp plates 19 provide upwardly extending portions 23 terminating into hook elements 24 facing outwardly with respect to the gunwale 14 when the clamp is attached to the gunwale as shown in Fig. 1.

A mounting structure is employed and comprises a frame 25 having diverging arms 26 and 26' perforated at their outer ends as at 27 for connection with the hook elements 24. The arm 26' is formed as an integral part of an extension plate 28. Substantially at the point of junction between the arm 26' and the plate 28 there is provided a bearing 29. This bearing 29 carries a pintle 30 which serves in one capacity to pivotally connect the arm 26 to the arm 26' whereby the arm 26 may be collapsed against the arm 26' when the oarlock is dismounted from the gunwale.

By pivotally connecting the arms 26 and 26' together the distance between the perforated end portions 27 may be adjusted to conform to the distance between the hook elements 24. This construction therefore eliminates the necessity of precision in manufacture of the parts.

The outer end portion of the plate 28 provides a bearing 31. Pivotally connected to this plate 28 are complementary oar bearing sockets 32 and 33.

The socket 32 is formed as an integral part of segmental plate 34 and provides a bearing 35 through which the pintle 30 projects for connecting the socket 32 and its plate 34 to the frame 25.

The socket 33 is likewise formed as an integral part of a segmental plate 36, and through a bear-

ing 37 this socket and its plate 36 are pivotally connected to the bearing 38 by a pivot 39.

These segmental plates 34 and 36 are arranged to oscillate in substantially the same plane and are provided, Fig. 3, with curved opposing surfaces 39. Each of these surfaces, Fig. 4 and Fig. 5, are provided with spaced parallel horizontally extending grooves 40 and 41. Fixed to the plate 34 as at 42, and extending over the curved surface 39 is one end portion 44 of a braided cable 43, with the opposite end portion 45 secured as at 46 to the plate 36. This cable 43, in its direction of extension from the plate 34 to the plate 36, is mounted in the grooves 40 of the opposing surfaces 39. A similar cable 47 has one end portion 48 connected as at 49 to the plate 36 and an opposite end portion 50 connected as at 51 to the plate 34, and this cable 47 bears in the grooves 41 of the opposing surfaces 39. The cables 43 and 47 cross each other at a point on the longitudinal axis of the plate 23 and provide an interconnection between the segmental plates 34 and 36, whereby these plates and the sockets carried thereby will oscillate in opposed directions with respect to each other.

It is desirable for frictional engagement between the base of the grooves 40 and 41 of the opposed surfaces 39 and the cables 43 and 47 that the direction of braiding of the strands of these cables be in opposite directions.

The means for connecting the ends of the cables to the segmental plates may be of any approved and desirable means. For instance, the ends 48 and 45 of the cables 47 and 43 respectively are connected to the plate 36 by imbedding the ends thereof in solder blocks 52 mounted in sockets 53 formed in the plate 36. The ends 44 and 50 of the cables 43 and 47 respectively have secured thereto nipples 54 which project through lugs 55 formed on the plate 34 and threaded on these nipples 54 are lock nuts 56.

The oars 57 are each divided into two portions 58 and 59. The portion 58 is provided with the paddle blade (not shown) whereas the portion 59 constitutes a handle. These portions 58 and 59 are mounted in the sockets 32 and 33 and may be fixed therein by suitable pins 60 which project through openings 61 formed in the sockets.

To complete the invention there is provided above the point of engagement between the cables 43 and 47 a suitable guard plate 62 which prevents dirt and grit from finding lodgment between the cables, and guards against accidental placement of the hand between the cables.

To attach the oarlock to the gunwale 14 of the boat 10, the clamps 19 are first attached to the gunwale 14. The arms 26 and 26' are then connected to the hooks 24. The oar portions 58 and 59 are mounted with their ends in their respective sockets 32 and 33.

The boatsman will occupy the seat forwardly of the rear seat 13 and face the bow of the boat. The handle or oar portions 59 are disposed forwardly of him. By manipulating these handles, rowing action will be transmitted to the oar portions 58 so as to row the boat in the direction toward which the boatsman is facing. By virtue of the perforations 27 and the hook elements 24, the oarlock may be tilted laterally with respect to the sides of the boat so as to dispose the oar portions 58 at a proper angle for rowing purposes and for lowering and elevating the paddle or blade portion of the oar into and from the water.

When detached from the boat, the oarlock may have the arms collapsed with respect to each

other so as to occupy the minimum of space when placed in storage when not in use.

The cable connections between the segmental plates 34 and 36 provide a silent movement of these plates and by virtue of their positive connection and frictional engagement in their respective grooves, a positive rowing action will result.

In Fig. 6 I have illustrated a modified form of clamp for clamping the oarlock to the gunwale 14. In this respect, hook elements 63, similar to the hook elements 24, are provided, but associated with each of these hook elements 63 is a sprung-urged safety pin 64 which releasably latches the perforated ends of the arms 26 and 26' within the hook elements 63.

The modified form shown in Fig. 5 is substantially similar to that shown in Figure 4, with the exception that an additional socket 65 is formed on the plate 34 in a position above the plane of the socket 33. This arrangement permits the mounting of the oar portion 58 as a continuation of the handle portion 59, whereby if for some reason the boatsman desires to row facing the stern of the boat, he may do so by merely mounting the oar portions 58 in the sockets 65.

From the foregoing description read in the light of the drawings, it will be apparent that I provide an oarlock capable of all the accomplishments hereinbefore set forth and that the same comprises relatively few parts thereby resulting in expeditious assembly and economical manufacture.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. An oarlock of the class described, comprising a frame having a pair of arms pivotally connected together for adjustment relative to each other, segmental plates arranged in opposed relation with respect to each other and pivotally carried by said frame, cable members connecting said plates together for oscillatory movement in opposite directions with respect to each other, clamping means for connecting the frame member to the gunwale of a boat, means providing pivotal connection between the arms of said frame member and said clamping means, socket elements on said plates, and oar portions mounted in said socket elements, one of said plates having an auxiliary socket element thereon, disposed in a plane above the socket of the other of the plates.

2. An oarlock of the class described, comprising a frame having a pair of arms pivotally connected together for adjustment relative to each other, segmental plates arranged in opposed relation with respect to each other and pivotally carried by said frame, cable members connecting said plates together for oscillatory movement in opposite directions with respect to each other, clamping means for connecting the frame member to the gunwale of a boat, means providing pivotal connection between the arms of said frame member and said clamping means, socket elements on said plates, and oar portions mounted

in said socket elements, said segmental plates having opposed curved surfaces providing tracks for said cable members, one of said plates having an auxiliary socket element thereon disposed in a plane above the socket of the other of the plates.
